UNITED STATES PATENT OFFICE.

CHARLES E. BALDWIN, OF NEW YORK, N. Y.

IMPROVEMENT IN ROTARY CHROMATIC HAND-STAMPS.

Specification forming part of Letters Patent No. 158,014, dated December 22, 1874; application filed November 7, 1874.

To all whom it may concern:

Be it known that I, CHARLES E. BALDWIN, of the city, county, and State of New York, have invented a new and Improved Rotary Chromatic Hand-Stamp, of which the following is a specification:

The invention will first be fully described, and then pointed out in the claim.

Figure 1 represents a side view of my invention. Fig. 2 is a plan of the same.

Similar letters of reference indicate corresponding parts.

In the case here presented the letter A represents a cylinder, on which the type is set. The said cylinder has its bearings in the arms of the frame B, and is held from making more than one revolution by the spring-catch C, which strikes against a pin or lug on the cylinder end. The ink and color rollers rest in slots D on the arc, forming bearings for them to revolve in, and are held in such position by elastic bands E, attached to rings slipped over their ends, and to a ring set over each end of the type-cylinder journals, as shown in Fig. 1. F F F F represent notches or rests, into which such rollers as are not required to be used are lifted, so as to clear them from the type-cylinder.

The drawing represents the device ready for printing in blue, red, and green, and showing the other rollers lifted out of connection with the type. It will thus be seen that by having

a set of rollers varied in form and position on the arc I am enabled to print any number of colors at one time with a single movement forward across the paper; but when it is desired to print in black or any single color, then it will be necessary to use a single roller, as G or H, and raise all the others off the type-cylinder into their respective rests F, thus combining a chromatic and plain style of printing in one device without taking anything off or adding anything to the roller-stamp, which is operated by grasping the handle I and pushing it forward in direction of arrow until the spring-catch strikes its stop on the cylinder end. The rollers, or such part or parts of them desired to contain the ink or color, are wrapped with flannel or its equivalent, so as to absorb a sufficient amount of coloring material to feed the type uniformly.

Having thus described my invention, I claim as new, and desire to secure by Letters Patent—

A hand printing-stamp provided with several inking-rolls, G H, each connected with the axis of type-roll by springs E E, and made to rest with their journals either in bearings F or D, as and for the purpose described.

CHARLES E. BALDWIN.
